INVENTOR,
W. D. OSBORN.
BY Martin P. Smith ATTY.

UNITED STATES PATENT OFFICE

2,050,500

EXERCISING HOBBYHORSE

William D. Osborn, Los Angeles, Calif.

Application January 15, 1934, Serial No. 706,660

2 Claims. (Cl. 272—55)

My invention relates to a combined exercising device and plaything particularly designed for children's use and the principal object of my invention is, to provide a toy or exercising device in the nature of a hobby horse that may be conveniently and safely used by children and which device when used affords pleasing amusement as well as a means for exercising practically all muscles of the body, arms and legs.

10 Further objects of my invention are, to provide an exercising plaything of the character referred to that is relatively simple in construction, inexpensive of manufacture and which may be readily adjusted for the accommodation of children of different weights.

15 A further object of my invention is, to provide an exercising plaything for children which when used will give the operator or rider the effect of riding a polo pony or other small animal.

20 With the foregoing and other objects in view my invention consists in certain novel features of construction and arrangements of parts that will be hereinafter more fully described and 25 claimed and illustrated in the accompanying drawing in which:

Fig. 1 is a side elevational view of an exercising plaything constructed in accordance with my invention.

30 Fig. 2 is a plan view of the exerciser.

Fig. 3 is an enlarged vertical section taken on the line 3—3 of Fig. 1.

Fig. 4 is a section taken on the line 4—4 of Fig. 3.

35 Referring by numerals to the accompanying drawing which illustrates a preferred embodiment of my invention, 10 designates a base rail which may be formed of wood or metal and secured to the underside of the end portions thereof 40 of are transverse rails 11 that are adapted to rest on the ground or floor.

Secured to the intermediate portion of rail 10, is the lower end of a post 12 and arranged between said post and base, are suitable braces 45 13.

The upper portion of post 12 is bifurcated for the reception of a tilting rail 14 and formed through the intermediate portion of this rail 14, is a series of transverse apertures 15.

50 A readily removable pin or bolt 16 passes through the upper portion of post 12 and through one of the apertures 15, thus forming an axis or fulcrum for the tilting rail 14.

Secured to the rear end of rail 14, is the upper end of a retractile spring 17 and seated in

the rear end of base rail 10, is a series of eyes 18, to any one of which the lower end of the spring 17 may be connected.

By providing the adjustable connection between the lower end of spring 17 and the rear portion of rail 10, and the adjustable fulcrum or point of pivotal connection between rail 14 and post 12, the device may be easily and conveniently adjusted for use by children of different weights.

10 Mounted on the forward end of rail 14, is an upwardly projecting panel 19 that is shaped to represent the head and neck of a small riding horse or polo pony and passing through the neck representing portion of this panel is a short rod 15 20, the projecting ends of which are adapted to be grasped by the user of the plaything.

Suitably secured on top of rail 14, just in front of the apertures 15, is a saddle representing seat 21 and secured to the forward end of rail 14 and 20 projecting forwardly and downwardly therefrom are members 22 that represent the front legs of a pony.

Secured to rail 14 adjacent to the front end of the seat or saddle 21 are downwardly and forwardly projecting arms 23 and seated in the lower ends thereof is a transversely disposed rod 24, the projecting ends of which serve as rests for the feet of the occupant of the seat or saddle.

Formed in the upper portion of the head and neck representing panel 19, is a recess 25 and passing therethrough and bearing in the walls to the sides of said recess, is a shaft 26. This shaft is mounted so as to rotate freely in its bearings and carried by the ends of the shaft that 35 project slightly beyond the sides of the panel 19, are upstanding members 27 of leather, fabric or analogous material and which are shaped to represent the ears of a pony.

Secured to shaft 26, within recess 25, is a counterbalancing weight 28 which swings backward and forward as rail 14 and panel 19 change their positions, such movement rocking the shaft 26 and moving the ear representing members 27 backward and forward, thus simulating the 45 backward and forward movement of a pony's ears.

The top of the recess 25 is closed by a thin sheet of material 29, preferably of metal.

In order to facilitate adjustment of the device for children of different weights, the apertures 15 and the eyes 18 may be distinctively designated, preferably by means of numerals placed on the base 10 adjacent to the eyes and on the beam 14 adjacent to the apertures therein.

In the use of my improved exercising play- 55

thing, a child is positioned on the seat or saddle 21 with the feet resting on the ends of rod 24 and the hands grasping the ends of rod 20. The child now moves the body slightly backward or forward and in so doing causes beam 14 to swing upon its axis and the upward movement of the rear end of said beam is yieldingly resisted by spring 17.

At the end of the upward swinging movement 10 of beam 14, the power stored in the spring during its expansive movement, will act to draw the rear end of beam 14 downward, which movement is accelerated by the rearward swinging movement of the rider's body and as these movements 15 are continued the beam 14 will swing vertically upon its axis, thereby providing a pleasing pastime as well as exercise of the body, arms and legs of the user of the device.

The axis or fulcrum between rail 14 and post 20 12 may be quickly and conveniently adjusted and the connection between the lower end of spring 17 and the rear portion of base 10 may likewise be conveniently adjusted, thus enabling the playing 25 thing to be adjusted for use by children of different weights.

Thus it will be seen that I have provided an exercising hobby horse that is relatively simple in construction, inexpensive of manufacture and very effective in performing the functions for 30 which it is intended.

It will be understood that minor changes in the size, form and construction of the various parts

of my improved exercising hobby horse may be made and substituted for those herein shown and described without departing from the spirit of my invention, the scope of which is set forth in the appended claims.

5

I claim as my invention:

1. In an exercising hobby horse, a base, a post projecting upwardly from said base, a rail pivotally mounted on the upper portion of said post, a seat mounted on said rail in front of said post, 10 a spring forming a connection between the rear end of said rail and said base, an animal head and neck representing panel mounted upon and projecting upwardly from the forward portion of said rail and counterbalanced ear representing 15 members mounted for rocking movement on the upper portion of said head and neck representing panel.

2. In an exercising hobby horse, a base, a post 20 projecting upwardly from said base, a rail pivoted on the upper portion of said post, a seat mounted on said rail in front of said post, a retractile spring forming a connection between the rear end of said rail and base, an animal head and neck 25 representing panel mounted on the forward portion of said rail there being a recess formed in the upper portion of said panel, a shaft journaled in said panel and passing through said recess, ear representing members carried by the 30 ends of said shaft and a counterbalancing weight carried by said shaft within said recess.

WILLIAM D. OSBORN.
